UNITED STATES PATENT OFFICE.

WILLIAM STANISLAU BILECK, OF FRANKLIN, KANSAS.

DRILL CONNECTION.

1,312,298.

Specification of Letters Patent. Patented Aug. 5, 1919.

Application filed October 3, 1916, Serial No. 123,572. Renewed January 9, 1919. Serial No. 270,444.

To all whom it may concern:

Be it known that I, WILLIAM STANISLAU BILECK, a citizen of the United States, residing at Franklin, in the county of Crawford, State of Kansas, have invented a new and useful Drill Connection; and I do hereby declare the following to be a full, clear, and exact description of the invention, such as will enable others skilled in the art to which it appertains to make and use the same.

The present invention relates to a quickly detachable joint for connecting drills to thread bars or feed screws, the object of the invention being to provide a connection of this kind which embodies novel features of construction whereby the drill can be quickly placed in position or removed therefrom, and which admits of the drill being pulled from the drill hole without the use of a small pin such as is ordinarily used.

Further objects of the invention are to provide a device of this character which is comparatively simple and inexpensive in its construction, which can be easily and quickly manipulated to place the drill in position or remove it therefrom, which securely locks the drill in position when the tool is in use, and which provides a secure connection between all of the parts for pulling the drill from the drill hole.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of a portion of a thread bar and drill, said members being connected by a quickly detachable joint constructed in accordance with the invention.

Fig. 2 is a similar view, taken at right angles to Fig. 1, parts being broken away and shown in section to bring out more clearly the manner of constructing and mounting the latch.

Fig. 3 is a detail perspective view of the polygonal head and latch at the end of the thread bar or feed screw.

Fig. 4 is a transverse sectional view on the line 4-4 of Fig. 2.

Fig. 5 is a detail sectional view through

the head at the end of the thread bar, showing a modified construction of the latch.

Corresponding and like parts are referred to in the following description and indicated in all the views of the drawings by the same reference characters.

Specifically describing the present embodiment of the invention, the numeral 1 designates the outer end of a feed screw or thread bar which may be of the conventional construction, said feed screw terminating in an enlarged polygonal head 2 which tapers slightly toward the free end thereof. A longitudinally extending recess 3 is provided in one side of the head 2, and a latch lever 4 is arranged within this recess, said latch lever being formed with a nose 5 which is adapted to engage a side opening 6 in a socket 7 which carries a conventional form of drill 8. This drill may be detachably connected to the socket by any well-known form of joint, such as that indicated at 9, the ends being secured together in operative position by a transverse pin 10.

The socket 7 has the same shape or configuration as the head 2 of the feed screw 1, and is flared or tapered in a corresponding manner, so as to accurately receive the same. The latch lever 4 is pivotally mounted at a point toward the outer end of the head 2 upon a transverse pin 10, the pivot end of the latch lever being formed with an inwardly extending arm 11 which is adapted to engage a shoulder 12 to limit the outward swinging movement of the lever and to relieve the pivot pin 10 of possible thrust when using the tool. A spring 13 is riveted to the back of the latch lever 4 and bears frictionally against the base of the recess 3 so as to normally tend to swing the latch lever outwardly into operative position, while an outwardly curved finger piece 4¹ at the swinging end of the latch lever projects from the recess 3 and provides a means for manipulating the latch lever to disengage the socket 7 from the head 2. A notch 14 is provided in the outer edge of the latch lever 4, said notch being sufficiently deep to receive a transverse pin 15. This pin serves both as a stop to limit the outward swinging movement of the latch lever, and also tends to relieve the pivot pin 10 of excessive longitudinal thrust when pulling the drill from the drill hole. This construction admits of the head and socket being quickly and securely fastened together, and there is no difficulty

in pulling the drill from the drill holder, the construction and arrangement of the parts being such that there is practically no danger of breakage.

5 A slight modification is shown by Fig. 5, in which the latch member 4^e is formed of a strip of spring material having one end thereof secured to the head by a suitable screw 16, while the opposite end thereof terminates in a finger piece 4^e. An intermediate portion of the spring strip is crimped to form a nose 5^e which operates in the same manner as the nose 5 in the previously described construction to engage the lateral opening 6 of the socket 7 and lock the socket securely in position upon the head 2. In order to release the socket from the head, the latch member is moved into inoperative position by pressing the finger piece 4^e inwardly. At a point above the nose 5^e, the spring strip may be crimped at 14^e for engagement with a transverse pin 15^e, said pin serving both to limit the outward swinging movement of the latch member, and also to relieve the fastening screw 16 of excessive longitudinal thrust when pulling the drill from the drill hole.

Having thus described the invention, what I claim as new and desire to secure by Letters Patent, is:—

1. In a device of the character described, the combination of a feed screw having a polygonal head at one end thereof, a drill provided with a socket adapted to receive the polygonal head and having a lateral opening in one side thereof, a pivoted latch member mounted upon the head and formed with a nose to engage the lateral opening of the socket to lock the members together, and means engaging the latch member to relieve the pivot of excessive longitudinal thrust.

2. In a device of the character described, the combination of a feed screw having a polygonal head at one end thereof, a drill provided with a socket adapted to receive the polygonal head, a pivoted latch member mounted upon the head for engagement with the socket to lock the members together, said latch member having a notch in one edge thereof, and a pin carried by the head and adapted to engage the notch to relieve the pivot of the latch member of excessive thrust.

3. In a device of the character described, the combination of a feed screw having a polygonal head at one end thereof, said head having a longitudinal recess in one side

thereof and a shoulder being provided toward the outer end of the recess, a drill provided with a socket adapted to receive the polygonal head, a latch member arranged within the recess of the polygonal head and pivoted toward the outer end thereof, said latch member being adapted to engage the socket to lock the members together, and a lateral arm at the pivot end of the latch member for engaging the before mentioned shoulder at the outer end of the recess.

4. In a device of the character described, the combination of a feed screw having a polygonal head at the end thereof, said head having a recess in one side thereof and a shoulder being provided at the outer end of the recess, a drill provided with a socket adapted to receive the polygonal head, a latch member arranged within the recess of the polygonal head and pivotally mounted toward the outer end thereof, said latch member having a notch in one edge thereof and being adapted to engage the socket to lock the members together, a lateral arm projecting from the pivot end of the latch member and adapted to engage the before mentioned shoulder of the recess, and a transverse pin extending across the recess for engagement with the notch of the latch member to relieve the pivot of the latch from excessive thrust.

5. In a device of the character described, the combination of a feed screw having a polygonal head at one end thereof, said head having a recess in one side, a drill provided with a socket adapted to receive the polygonal head and having a lateral opening in one side thereof, a latch member pivotally mounted within the recess of the head and provided with means adapted to engage the lateral opening of the socket to lock the two members together, said latch member also having a notch in one edge thereof, a transverse pin extending across the recess for engagement with the notch to relieve the pivot of the latch member of excessive thrust, and a spring acting upon the latch member to normally swing the same outwardly into operative position.

In testimony whereof I have signed my name to this specification in the presence of two subscribing witnesses.

WILLIAM STANISLAU BILECK.
